UNITED STATES PATENT OFFICE.

HARRISON D. BOYER, OF PHILADELPHIA, PENNSYLVANIA, ASSIGNOR, BY MESNE
ASSIGNMENTS, TO LEANDER W. RIDDLE, OF GLEN RIDDLE, PENNSYLVANIA.

LUBRICATOR.

1,304,536.

Specification of Letters Patent. Patented May 27, 1919.

Application filed April 4, 1914, Serial No. 829,568. Renewed January 17, 1919. Serial No. 271,763

To all whom it may concern:

Be it known that I, HARRISON D. BOYER, a citizen of the United States, residing at Philadelphia, in the county of Philadelphia and State of Pennsylvania, have invented 5 new and useful Improvements in Lubricators, of which the following is a specification.

My invention relates to new and useful 10 improvements in lubricators, and has for its object to provide an exceedingly simple and effective construction which will provide for the feeding of grease or other lubricant to the bearings of machinery, the principal 15 object of my present invention being to overcome the necessity of threading the outside of the cup, and the inside of the cap, which usually threads therein, thus providing a closer fit between these members to 20 prevent the leakage of the lubricant therebetween.

With these ends in view this invention 25 consists in the details of construction and combination of elements hereinafter set forth and then specifically designated by the claims.

In order that those skilled in the art to 30 which this invention appertains may understand how to make and use the same, I will describe its construction in detail, referring 35 by numerals to the accompanying drawings forming a part of this specification, in which—

Figure 1, is a central vertical section of a 40 lubricator made in accordance with my improvement.

Fig. 2, is a side elevation of the cap; and

Fig. 3, is a plan view of the cap.

Fig. 4, is a view similar to Fig. 1 illustrating the position of the parts when the 45 contents of the lubricator is under pressure.

In carrying out my invention as embodied, 1 represents the base or stand of a lubricator having formed therewith the 50 threaded nipple 2 which is adapted to be screwed into the bearing to be lubricated, and the upper portion of this case carries the thread post 3, said post being adapted to receive the sleeve 4 which is internally 55 threaded to correspond therewith. This sleeve is here shown as secured to the cap 5, but may be formed therewith, said cap being adapted to slide within the cup 6, the latter being secured upon the base in any

convenient manner here shown as being so 55 secured by upsetting the upper edge of the shoulder 10 over the bottom of the cup.

The threaded post has a cross passage 7 formed therethrough, which intersects the vertical passage 8, the latter being the outlet for the lubricant.

By this arrangement the lubricant upon which pressure is exerted by the air in the cap as the latter is threaded or screwed down is forced through the cross passage 65 7, into the vertical passage 8, and thence to the bearing as will be readily understood.

The top of the cap has corrugations 11 formed thereon so as to increase its flexibility, and on top of this cap so as to cover the 70 corrugations is placed a cover 12, said cover being in the form of an ordinary box base top having a central opening 13 therein, and pivot sockets 14 for the reception of the 75 pivot tangs 15 of the signal 16. Projecting upward from the top 11 is a lug 17 which bears upon the lower edge of the signal in such manner as to elevate said signal when the top is in its normally elevated position.

When the lubricating material is placed 80 in the lubricator and the sleeve is threaded downward or inward, the central portion of the top of the cap will be drawn inward as plainly shown in Fig. 4 so as to increase the distance or space between the top of the 85 cap and the cover 12 in the region of the central parts thereof, thereby removing the pressure of the lug 17 from the underside of the signal 16, permitting the latter to swing downward or to a horizontal position. This 90 action can only take place when the lubricator is filled with or contains a lubricant and while the outer circumference of the top of the cap 5 remains in its last position by the pressure of the trapped air, the central 95 portion is drawn inward by screwing the sleeve upon the threaded post 3 and said signal 16 will remain in the horizontal position so long as sufficient pressure is maintained within the cap, but when this pressure is relieved by the expulsion of the lubricant from the lubricator, the top will again flex to its normal position and cause the outer circumference of the top of the cap 5 to move to a position which will bring 100 said outer circumference into the same plane as the central portion of the top of the cap and this action will shorten the distance be-

tween the central portions of the top of the cap and the cover 12 which will cause the lug 17 to elevate the signal, indicating that the cup needs to be set up.

5 Of course I do not wish to be limited to the exact details of construction as here shown, as these may be varied within the limits of the appended claims without departing from the spirit of my invention.

10 Having thus fully described my invention, what I claim as new and useful, is—

1. In a device of the character described a base having a threaded post projecting upwardly therefrom, a cup carried by the

15 base, a cap fitted to slide in the cup, a sleeve projecting downward from the top of the cap and adapted to thread on the post, a semaphore carried by the cap and means also carried by the cap for operating said 20 semaphore.

2. In a device of the character described, a base having a threaded post projecting upwardly therefrom, a cup carried by the base, a cap fitted to slide in the cup and

25 having threaded engagement with the post, the top of said cap being flexible, a top carried by the cap, a semaphore pivoted to the top and means carried by the flexible top for operating said semaphore.

30 3. In a device of the character described a base having a central longitudinal opening therein, and a threaded post formed integral therewith, said post having a transverse opening therethrough communicating

35 with the opening in the base, and also having a shoulder, a cup carried by the base and adapted to be secured in position by upsetting the upper edge of said shoulder, a cap fitted to slide in the cup, and a sleeve carried by the top of the cap and projecting from the center thereof, said sleeve 40 adapted to thread upon the post.

Copies of this patent may be obtained for five cents each, by addressing the "Commissioner of Patents, Washington, D. C."

4. In a lubricator a cap, a semaphore carried by the cap and means also carried by the cap for operating said semaphore. 45

5. In a lubricator a cap, the top of which is flexible, a top carried by the cap, a semaphore pivoted to the top, and means carried by the cap for operating said semaphore.

6. In a lubricator a cap having a flexible 50 top, a top carried by said cap, said cap and top having portions spaced apart, a semaphore pivoted to said second mentioned top and means carried by the flexible top of the cap for operating said semaphore.

7. A lubricator consisting of two members, one of which is movable with relation to the other, said movable member having a flexible top, a top member having a central opening and pivot sockets secured to 60 the movable member, a semaphore mounted in the pivot sockets, and means carried by the flexible top for operating said semaphore.

8. A lubricator consisting of a cup member, a cap member coöperating therewith, corrugations formed on the top of the cap member to increase its flexibility, a lug projecting from said flexible top of the cap member, a top member having a central 70 opening and pivot sockets secured to the cap member, and a semaphore having tangs, said tangs being mounted in the pivot sockets so that the lug bears upon the lower edge of said semaphore, so as to elevate the same 75 when the pressure in the lubricator is relieved.

In testimony whereof, I have hereunto affixed my signature in the presence of two subscribing witnesses.

HARRISON D. BOYER.
